H. LERNER.
ELECTRIC LAMP STAND,
APPLICATION FILED DEC. 10, 1920.

1,383,132.

Patented June 28, 1921.

Inventor:
Harry Lerner
By his Attorney *Alfred Bloch*

UNITED STATES PATENT OFFICE.

HARRY LERNER, OF BROOKLYN, NEW YORK.

ELECTRIC-LAMP STAND.

1,383,132.

Specification of Letters Patent. Patented June 28, 1921.

Application filed December 10, 1920. Serial No. 429,727.

To all whom it may concern:

Be it known that I, HARRY LERNER, a citizen of the United States, and a resident of the borough of Brooklyn, county of Kings, 5 city and State of New York, have invented certain new and useful Improvements in Electric-Lamp Stands, of which the following is a specification.

My invention relates to improvements, in 10 electric incandescent desk or stand lamps and contemplates by its construction to be utilized equally as a lamp which may be set upon flat surfaces or which may be clamped if desired to a ledge or projection or to a 15 bed post so as to be adjustable to a variety of positions, the construction disclosed being one of extreme simplicity but possessing great utility and ornamentation of design.

Reference is to be had to the accompanying drawings wherein Figure 1 is an elevation of the lamp socket and its hood with my improved base and standard in vertical cross section: Fig. 2 is a section taken on 20 line 2—2 of Fig. 1 and Fig. 3 is a section on line 3—3 of Fig. 1.

Having reference to these drawings 4 represents the base plate of my lamp, the under side of which is adapted to rest upon flat 30 surfaces as those of a desk or table. This base plate, as shown in the drawings toward its central portion projects upwardly in the form of a cone; 5 represents a tube or stem secured as by solder, to the central portion 35 of said base plate 4 and extends vertically therefrom; 6 represents a lower extension of the lamp socket 7 wherein the lamp socket is detachably mounted, said extension having a lower projection 6^a of reduced diameter.

To serve as a handle and for the purpose also of serving as a clamping member, as hereinafter described I provide a laterally extending hooked member 8 having a tongue 45 8^a entering a slot 8^b in the lower end of the tube 5. This tongue 8^a of said handle is connected to a spiral spring 9 extending from the lower end of the tube upwardly

and into the annular extension 6^a of the socket 7 where it is anchored to a cross bar 50 or pin 10. The handle 8 and its tongue 8^a are fulcrumed in the slot 8^b as at 8^c between the base 4 and the lower end of the stem 5. From the foregoing description it will appear that the spring 9 exerts tension upon 55 the handle or lever 8 and thus maintains the handle 8 in normal or closed position, as shown in Fig. 1, i. e. in contact with the rimmed upper face of the base plate 4, thus affording a convenient and ornamental 60 handle therefor. When it is desired to attach the lamp to a table or to a bed post the outer hooked end of the handle 8 is raised against the tension of the coiled spring 9 and engages between its under side 65 and the upper face of the base plate 4 the article to which the lamp is required to be clamped. In order to afford considerable latitude of movement for the socket 7 a portion of the upper end of tube 5 is cut away 70 to form a pair of ears 11.

It will be understood that in the construction shown the hood or shade 12 may be revolubly mounted at the upper end of the socket and that the insulated wire supplying the current to the socket will be carried through the base plate and through the tube 5 for connection with the socket 7 in the usual manner.

What I claim and desire to secure by Letters Patent is:

An electric lamp-stand comprising a base-plate and a vertical tube therefor, a socket pivotally secured upon a cross-pin carried at the upper end of said tube, a coiled spring 85 extending from the base plate through said tube and secured to said cross-pin, and a handle extending laterally from said tube pivotally movable and engaged by the lower end of said coiled spring and coöperating with said base plate to clamp the lamp stand to an article of furniture.

In witness whereof I have hereunto set my hand this 4th day of December, 1920.

HARRY LERNER.
